US0D1108002S

(12) **United States Design Patent** (10) **Patent No.:** **US D1,108,002 S**
(45) **Date of Patent:** **** Dec. 30, 2025**

(54) **AEROSOL GENERATOR**

(71) **Applicant:** **NICOVENTURES TRADING LIMITED**, London (GB)

(72) **Inventors:** **Jared Aller**, Winston Salem, NC (US); **Christina Tapp**, Winston Salem, NC (US); **Kang Min Kim**, London (GB); **William Webb**, San Francisco, CA (US); **Vic Pramono**, Winston Salem, NC (US)

(73) **Assignee:** **NICOVENTURES TRADING LIMITED**, London (GB)

(**) **Term:** **15 Years**

(21) **Appl. No.:** **29/877,470**

(22) **Filed:** **Jun. 7, 2023**

(30) **Foreign Application Priority Data**

Dec. 13, 2022 (EM) 015006087-0005

(51) **LOC (15) Cl.** **27-07**

(52) **U.S. Cl.**

USPC **D27/162**

(57) **CLAIM**

The ornamental design for an aerosol generator as shown and described.

DESCRIPTION

FIG. 1 is a top front perspective view of an aerosol generator showing the claimed design;

FIG. 2 is a bottom rear perspective view thereof;

FIG. 3 is a top front perspective view thereof;

FIG. 4 is a top view thereof;

FIG. 5 is a bottom view thereof;

FIG. 6 is a front view thereof;

FIG. 7 is a rear view thereof;

FIG. 8 is a right view thereof; and,

FIG. 9 is a left view thereof.

The evenly spaced broken lines in the drawings depict portions of the aerosol generator that form no part of the claimed design.
